ERASER

John H. Morcom, Long Beach, Calif.

Application January 17, 1939, Serial No. 251,347

6 Claims. (Cl. 120—36)

This invention relates to erasers.

The general object of the invention is to provide a disk eraser with novel means for maintaining the erasing member clean and sharp.

5 A more specific object of the invention is to provide a disk eraser including a body portion with an abrasive member slidably in the body portion and normally urged toward the eraser.

Another object of the invention is to provide a 10 novel means for mounting an abrasive member on a disk eraser.

Other objects and the advantages of this invention will be apparent from the following description taken in connection with the accompanying 15 drawing, wherein:

Fig. 1 is a side elevation of an eraser embodying the features of my invention;

Fig. 2 is a side elevation of the eraser with one of the side members removed;

10 Fig. 3 is a section taken on line 3—3 of Fig. 1;

Fig. 4 is a perspective view of the abrasive member;

Fig. 5 is an enlarged fragmentary view showing a modified form of abrasive member;

15 Fig. 6 is a perspective view showing the modified form of abrasive member;

Fig. 7 is a fragmentary side elevation showing a modified sharpening member;

Fig. 8 is a section taken on line 8—8 of Fig. 7;

20 Fig. 9 is an elevation, partly in section, showing a further modified knife; and

Fig. 10 is a section taken on line 10—10 of Fig. 9.

Referring to the drawing by reference characters I have shown my invention as embodied in 25 an eraser which is indicated generally at 10 and which includes the usual circular or disk-like eraser member 11 and a handle portion 12. The handle portion 12 includes a pair of body members 13 and 14.

The body members 13 and 14 are secured together at each end by pins 15 and 16, each of which includes a pair of members comprising a hollow internally threaded cylindrical shaft 17 with a threaded head member 18 which engages the hollow shaft.

5 The eraser 11 is rotatable in the pin 15 while the other pin 16 is fitted in an aperture 19 in the body 20 of a removable brush 21. The body members 13 and 14 have opposed complementary recesses 22 and 23 which receive the brush body and tightly engage the same.

The body members 13 and 14 include other opposed slots 24 and 25 in which an abrasive member 26 is slidably mounted. The abrasive member is made of suitable gritty material and preferably

includes a rectangular body 27 having a hole 28 in one end and having a V-shaped notch 29 in the other end which notch is adapted to engage the edge of the eraser. The shape of the notch 29 will be determined by the shape in which it is desired to maintain the eraser edge.

A spring 30 has one end arranged in the hole 28 and has its other end engaging in a hole 31 formed in the end wall 31' which defines the end of the slots 21 and 22. In use the parts are assembled 10 and the headed members 18 are turned into securing position.

The eraser is used in the usual manner and in order to sharpen the erasing edge thereof the eraser is turned causing its edge to move in the 15 notch 29. The spring 30 urges the abrasive member towards the eraser and thus as the eraser is worn away the sharpening and cleaning action is not interfered with.

20 In Figs. 5 and 6 I show a modification of my invention wherein the abrasive member comprises two portions 32 and 33 which have a hole 34 therein and which have bevelled ends 35. Strips of abrasive material 36 such as sand paper, emery cloth, etc. are arranged over the bevelled 25 portions 35 and have their outer ends folded over and disposed in slots 37 which have enlarged inner ends 38 to receive the folded over portion and thus anchor the strip in place. The inner ends of the strips 36 may have similar folded over 30 ends inserted in slots 39 having enlarged portions 40.

25 In Figs. 7 and 8 I show a modified abrasive member which is indicated generally at 50 and which is similar to the member 26 previously described except that the notch 51 which engages the eraser 52 has an arcuate edge 53 at the juncture of the sides of the V and this edge is defined by an arc whose radius is longer than the radius defining the edge 54 of the eraser.

30 In Figs. 9 and 10 the abrading or cutting member 55 is made of metal or other suitable material and includes a pair of spaced hard metal knife members 56 which are embedded in the member 55 and which include V-notches which engage 45 the edge of the eraser to perform the scraping or cutting operation.

35 From the foregoing description it will be apparent that I have invented a novel self-cleaning and self-sharpening eraser which can be economically manufactured and which is highly efficient for the intended purpose.

Having thus described my invention I claim:

40 1. In an eraser, a body, a circular eraser rotatably mounted on said body, said body having a 55

- slot therein, an abrasive member slidable in said slot, said abrasive member having a V-shaped edge thereon adapted to engage the eraser edge, and a spring having one end engaging the body and the other end of said spring engaging the abrasive member.
2. In an eraser, a body, a circular eraser rotatably mounted on said body, said body having a slot therein, an abrasive member slidable in said slot, said abrasive member being made of a single piece of material and having a notched edge thereon adapted to engage the eraser edge, and means to urge said abrasive member against the eraser.
15. 3. In an eraser, a body comprising a pair of members, means to secure said members together, said means including a pair of pins, a circular eraser rotatably mounted on one of said pins, an abrasive member slidable on said body, 20 said member having a V-shaped edge thereon adapted to engage the eraser edge, and means to urge said abrasive member against the eraser edge.
4. In an eraser, a body, a circular eraser rotatably mounted on said body, said body having a slot therein, an abrasive member slidable in said slot, said abrasive member having a V-

shaped edge thereon adapted to engage the eraser edge, said abrasive member having a recess therein, and a spring disposed in said recess and having one end engaging the end wall of the recess, the other end of said spring engaging the body. 5

5. In an eraser, a body, a circular eraser rotatably mounted on said body, said body members having a slot therein, an abrasive member slidable in said slot, said abrasive member comprising two similar portions each having a bevelled edge, a piece of abrasive sheet material fitting over the bevelled edges, means to hold the abrasive sheets in place, said bevelled portions forming a notch receiving the eraser edge and means to urge the abrasive member against the 15 eraser.

6. In an eraser, a body, a circular eraser rotatably mounted on said body, said body having a slot therein, an abrasive member slidable in said slot, said abrasive member having an arcuate 20 end portion which is V-shaped in cross section and adapted to engage the eraser edge, and a spring having one end engaging the body and the other end of said spring engaging the abrasive member.

JOHN H. MORCOM.
